UNITED STATES PATENT OFFICE.

ERNST TIMMERHOFF, OF ELKHART, INDIANA.

DESIGN FOR A HOUSING FOR SCREEN-ROLLERS.

SPECIFICATION forming part of Design No. 33,738, dated December 18, 1900.

Application filed November 21, 1900. Serial No. 37,295. Term of patent 7 years.

To all whom it may concern:

Be it known that I, ERNST TIMMERHOFF, a citizen of the United States, residing at Elkhart, in the county of Elkhart and State of Indiana, (post-office address No. 11 Simontan street, Elkhart, Indiana,) have invented and produced a new and original Design for a Housing for Screen-Rollers; and I do hereby declare the following to be a full, clear, and exact description of the invention, such as will enable others skilled in art to which it appertains to make and use the same.

This invention relates to the design for a screen-roller housing; and it consists of the characteristic features hereinafter set forth, and more particularly illustrated in the accompanying facsimile drawings, in which—

Figure 1 is a top perspective view of the housing. Fig. 2 is a bottom perspective view. Fig. 3 is a view of the lower end. Fig. 4 is a cross-section of the housing, looking toward the upper end.

Corresponding and like parts are referred to in the following description and indicated in all the views of the drawings by the same reference characters.

The essential feature of the invention is a cylindrical body having capped ends and a longitudinal slot in one side, the rims of the caps banding the end portions of the body and having notches in coincident relation with the slot in the side thereof, the upper cap having an outer wing and a central opening and the lower cap a central dish-shaped portion formed with an oblong opening, a series of

triangular-shaped openings grouped about the central part, spurs of triangular form at one side of the openings of corresponding shape and extending outward from the cap, at a right angle to the plane thereof, and a wing in the plane of the crown.

The body 1 of the housing is cylindrical in form and has a longitudinal slot 2 in one side and is capped at its ends, the rims of the caps appearing as bands and constituting annular offsets at the ends of the cylindrical body. The cap 3 has a central opening 4 and an outer wing 5 at one side pierced at 6. The cap 7 has a central dished portion 8, having an oblong opening 9 medially thereof. Triangular-shaped openings 10 are located in the marginal portion of the cap surrounding the dished part 8, and spurs 11 of corresponding form are located at one side of the openings and project outward at a right angle from the plane of the cap. A wing 12 projects laterally from the crown of the cap 7, in the plane thereof, and is pierced to receive fastenings. The bands of the caps have notches 13 to register with the ends of the slot 2.

Having thus described the invention, what is claimed as new is—

The design for a housing for screen-rollers, substantially as herein shown and described.

In testimony whereof I affix my signature in presence of two witnesses.

ERNST TIMMERHOFF. [L. S.]
